UNITED STATES PATENT OFFICE.

SIDNEY B. BLAISDELL, OF PROVIDENCE, RHODE ISLAND, ASSIGNOR TO RHODE ISLAND BRAIDING MACHINE COMPANY, OF PROVIDENCE, RHODE ISLAND, A CORPORATION OF RHODE ISLAND.

BRAIDING MACHINE.

Application filed June 24, 1925. Serial No. 39,294.

This invention relates to an improved construction of braiding machine, and has for its object to provide a braiding machine with two separate and independent braiding units supported on a single frame, whereby the waste space in the center of the usual larger size braider is occupied by a smaller braider unit.

A further object of this invention is the provision of a braiding machine having two separate raceways, one within the other and a separate set of carriers in each raceway operated to work independently of each other to produce independent braided work.

A still further object of the invention in addition to reducing the floor space is to reduce the weight of the machine, which is accomplished by constructing the two machines practically in one with the result that my combination machine weighs much less than would two separate machines constructed to produce the same result. It is also obvious that the more compact the machine the less floor space taken up and, therefore, the greater the number of braiding units operable by each attendant.

With these and other objects in view, the invention consists of certain novel features of construction, as will be more fully described, and particularly pointed out in the appended claims.

In the accompanying drawings:

Figure 1 is a front elevation of my improved braiding machine.

Figure 2 is a top view of the machine partly broken away showing an arrangement of the two separate raceways for the two separate braiding units.

Figure 3 is a detail partly in section showing the mechanism by which one of the units may be operated by hand.

Figure 4 is a side elevation of my improved machine illustrating the two separate braiding units including the two take-up mechanisms for the two different braids produced.

Figure 5 is a top view illustrating the arrangement of the two sets of horn gears for

driving the two different sets of braiding carriers.

Figure 6 is a fragmental view in elevation illustrating the two sets of horn gears and the mechanism by which both sets may be driven in unison; also showing the clutches by means of which either set may be disengaged from the driving mechanism and the other set driven independently thereof.

Figure 7 is a modification showing a plan view to illustrate extra sets of take-off rolls as leading the two braids into separate cans.

Figure 8 is a front elevation showing a fragmental view of the parts illustrated in Figure 7, showing the small gears as driving the extra set of rolls from one of the take-up head drive shafts.

It is found in the practical operation and construction of braiding machines of this character, particularly in the larger size machine for braiding flat braid, that the space in the center portion of the machine, is not occupied and is, therefore, wasted and as floor space in mills is of great value it is, of course, of advantage to utilize this space to the greatest advantage; also it is advantageous to reduce the weight of machines of given capacity to the minimum consistent with other requirements. Therefore, in order to reduce the floor space to be taken up by braiding machines of this character and also to reduce the weight to the minimum, I have devised a simple and practical way of utilizing this space which is within the raceway of the larger size machine by mounting another braiding unit in this center portion, which unit may be started and stopped independently of the larger unit but which may be driven synchronously with the larger unit from the main driving shaft thereof, if desired. This smaller unit may also have its separate and independent braid take-up mechanism, and in a machine for braiding flat braid a space at the front of the larger unit is quite sufficient to permit the manipulation of the different threads in the smaller unit without interfering one with the other;

and the following is a detailed description

of the present embodiment of my invention and showing one construction of braiding machine whereby these advantageous results may be accomplished:—

- 5 With reference to the drawings, 10 designates the table of my improved combination braiding machine which is supported on legs 11 and on this table is supported the raceway plate 12 which is provided with an 10 outer raceway 13 of the larger size machine, which extends part way around the circle of the raceway plate 12 being of the type arranged for the braiding of flat braid. A raceway formed on this relatively large 15 circle must necessarily leave a substantial central portion unoccupied, in the ordinary braider, and in order to utilize this heretofore unused space to advantage, I have formed another or inner raceway 14 with 20 in the outer raceway 13 in the same raceway plate 12. The turn quoits 15 of the inner raceway may be set opposite to the turn quoits 16 of the outer raceway or they may be set adjacent to them 25 if desired and in either case the yarn leading from the different carriers may be led to their respective braiding points without those of one set interfering with those leading from the other set of carriers. The 30 yarn 19 from the carriers 17 of the outer raceway being led along their selvage needles 18 to be braided together at the point 20 and thence led over the roll 21 and the set of rolls 22 in the take-up head 81 to be wound 35 on the reel 23, while the yarns 24 from the carriers 25 are led over the selvage needles 26 to be braided at the point 27 thence over the roll 28 and series of rolls 29 in the take 40 head 82 to be wound on the reel 30. Both of these take-up heads are mounted adjacent the axial center of the machine and both are supported on the single take-up head supporting frame 83 which is supported on the cross-bar 84 and back brace 45 85. It is obvious that the smaller raceway may be continuous in itself to permit the braiding of tubular braid thereon, if desired.
- 50 The power for driving the two units is herein described as being adapted to be applied through a large pulley 31 mounted on the main drive shaft 32 which has its bearings at 45 and 46, respectively, the outer end of this shaft 32 transmitting its power 55 through the mitre gears 33, clutch members 34, and sliding clutch member 38, upright shaft 35 and gear 36 to drive a train of horn gears 37 for imparting a braiding motion to the set of carriers 17.
- 60 This main shaft 32 may also be employed to transmit motion through mitre gears 39, clutch member 40, movable clutch member 41, upright shaft 42 and gear 43 to the train of horn gears 44 to impart the necessary

braiding action to the set of carriers mounted in the inner raceway 14.

In order to impart a rotary motion to the take up I have mounted a pair of gears 47 to receive motion from the upright shaft 42 and transmit the same through shaft 48, 70 mitre gears 49, upright shaft 50, worm 51, worm gear 52, gears 53 and 54, to horizontal shaft 55 for the purpose of rotating the take up rolls 29, also transmitting power from the lowermost of this set of rolls 29 through 75 pulley 56, belt 57, pulley 58 to the reel 30, also on this upright shaft 50 I have mounted an operating handle 59 by which the mechanism of the smaller unit may be operated by the attendant when desired, independently of the driving power from the main shaft; also, a set of take-up rolls 22 are arranged to receive power from the upright shaft 35 through worm 60, worm gear 61, gears 62, large gear 63, horizontal shaft 80 64 for the purpose of taking up the braid work as produced by the outer braiding unit, which power is transmitted through the lower roll of the group 22 through the pulley 65, belt 66, pulley 67 to the take-up 90 reel 23. Also, this unit may be operated by hand if desired by manipulating the handle 80.

The stop mechanism for each unit is entirely separate, that actuated by the carriers 95 of the larger braiding unit being a lever 68 pivoted at 69 having an inwardly extending loop portion 70 adapted to be engaged by the usual tension weight on the carrier when the end is broken to throw this lever out of 100 engagement with the upright lever 71 to permit the clutch member 38 to drop out of engagement with the member 34 thereby disconnecting the power from the larger unit permitting its mechanism to stop until 105 the operator has pieced up the end and restored the mechanism to its running position.

When a yarn end breaks in the smaller or central unit the knock-off lever 72 pivoted at 73 is engaged at the point 74 and thrown outwardly to release the upright lever 75 permitting the clutch member 41 to drop out of engagement with the clutch member 40 to arrest the action of the smaller braiding 115 unit until this end is pieced up and the parts again restored to operating position.

It will also be noted that by the arrangement of the two different raceways that the stop motion of the inner raceway is so positioned as to arrest the carrier with the broken end, at a point directly at the front of the machine, where it is most accessible to the operator.

The braided work after being taken up by the take-up head may be taken off by the reels 23 and 30 shown in Figure 4, or by suitable take-off rolls 76 and 77 on shafts

64 and 55, respectively, and delivered into cans 78 and 79 or other receptacles, if desired.

By my improved construction of braiding machine it will be seen that I may operate each of its braiding units independently of the other, one may be caused to make one kind of braid while the other, at the same time may make another braid of an entirely different character, again by my improved arrangement of braiding units practically the whole of the space now occupied by the second or smaller braiding unit has heretofore been unoccupied or wasted, which space by my improved construction is now utilized, and in addition I now employ the same bed, legs, main driving shaft and pulley used by the larger unit, for the smaller unit, thus saving the weight of these parts in the construction of the second unit by eliminating the necessity of duplicating the same in the production of this smaller unit.

In addition to the above it is also obvious that by mounting the machine in a more compact space more machines may be operated by a single attendant.

The foregoing description is directed solely towards the construction illustrated, but I desire it to be understood that I reserve the privilege of resorting to all the mechanical changes to which the device is susceptible, the invention being defined and limited only by the terms of the appended claims.

85 I claim:

1. In a braiding machine, two separate and independent braiding units supported on a single frame, one being partially surrounded by the other.

40 2. In a braiding machine, two separate and independent braiding units supported on a single frame, one within the other, and means for controlling the action of each unit independently.

45 3. In a braiding machine, two separate and independent braiding units supported on a single frame, one raceway being within the confines of the other, and mechanism for starting and stopping each independently.

50 4. In a braiding machine, two separate and independent braiding units supported on a single frame, one unit being partially surrounded by the other, mechanism for starting and stopping each independently, and means whereby each may be driven in unison if desired.

55 5. A braiding machine having two separate and independent raceways, one partly within the confines of the other and a set of carriers in each raceway adapted to work in their respective raceway independently of each other to produce independent braiding results.

6. A braiding machine having two sepa-

rate and independent raceways, one being 65 partially surrounded by the other, a separate set of carriers operatively mounted in each raceway to work independently of each other and mechanism for taking up the work of each separately as formed. 70

7. A braiding machine having a raceway table with two separate and independent raceways formed therein, one being partially within the other, a set of carriers mounted to operate independently in each raceway, 75 separate take-up mechanisms for the work of each set, and clutch mechanism through which each set may be operated independently.

8. A braiding machine having two separate and independent braiding units one partly within the confines of the other, co-operating juxtaposed yarn take-up heads for said units and a braid take-off cooperating with each head. 85

9. A braiding machine having separate and independent braiding units the raceway of one being partially surrounded by that of the other, cooperating juxtaposed yarn take-up heads for said units and a take-off 90 device cooperating with each head; said take-up and take-off mechanisms for each unit being connected to be operated only with that braiding unit of which it is a part. 95

10. In a braiding machine, two separate and independent braiding units the raceway of one being partially surrounded by that of the other, cooperating juxtaposed yarn take-up heads for said units located on opposite sides of the axial center of the machine, and 100 a take-off device cooperating with each take-up head for taking care of the braid as finished.

11. A braiding machine having two separate and independent braiding units operatively mounted therein, the raceway of one being partially within the confines of that of the other, each unit having a separate braid take-up head located adjacent the axial center of the machine, and a take-off 110 reel for each take-up head on which the braid is wound as formed. 105

12. A braiding machine having two separate and independent raceways, one being partially surrounded by the other, the turn 115 quoits of the outer raceway being spaced a substantial distance apart to permit easy access to the mechanism of the other braiding unit within.

13. A braiding machine having two separate and independent raceways, one being partially surrounded by the other, the turn quoits of the outer raceway being spaced a substantial distance apart and stop mechanism for the carriers of the inner raceway 125 being located in the space intermediate the turn quoits of the outer raceway. 120

14. A braiding machine having two sepa-

rate and independent braiding units operatively arranged therein, including two sets of carriers, a single head frame for both units, a cross-bar and back brace supporting said frame on said machine above the path of its carriers, and two separate braid take-up devices mounted on said head frame.

15. A braiding machine having two separate and independent units, the raceway of

one being partially within the confines of ¹⁰ that of the other, a main drive, independent mechanism for operating said different units individually, and clutch mechanism interposed intermediate said main and individual drives whereby said individual drives may ¹⁵ be either jointly or separately operated.

In testimony whereof I affix my signature.

SIDNEY B. BLAISDELL.
